US00D781409S

(12) **United States Design Patent** (10) **Patent No.:** **US D781,409 S**
(45) **Date of Patent:** **** Mar. 14, 2017**

(54) **OVATE FILTER CARTRIDGE END CAP**

(71) Applicant: **Donaldson Company, Inc.**,
Bloomington, MN (US)

(72) Inventor: **Thomas D. Raether**, St. Louis Park,
MN (US)

(73) Assignee: **DONALDSON COMPANY, INC.**,
Bloomington, MA (US)

(**) Term: **14 Years**

(21) Appl. No.: **29/482,757**

(22) Filed: **Feb. 21, 2014**

(51) LOC (10) Cl. **23-04**

(52) U.S. Cl.

USPC **D23/386**

(58) **Field of Classification Search**

(57) **CLAIM**

The ornamental design for an ovate filter cartridge end cap, as shown and described.

DESCRIPTION

FIG. 1 is a front perspective view of an ovate filter cartridge end cap of the claimed design;

FIG. 2 is front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the figures do not form a part of the claimed design.

1 Claim, 5 Drawing Sheets
